UNITED STATES PATENT OFFICE.

EDWARD POSSON, OF CHICAGO, ILLINOIS, ASSIGNOR TO GRAIN BELT CAR SPECIALTY COMPANY, A CORPORATION OF MAINE.

GRAIN-DOOR.

977,042.

Specification of Letters Patent. Patented Nov. 29, 1910.

Application filed July 6, 1908. Serial No. 442,010.

To all whom it may concern:

Be it known that I, EDWARD POSSON, a citizen of the United States, residing at Chicago, in the county of Cook and State of Illinois, have invented certain new and useful Improvements in Grain-Doors, of which the following is a specification.

The object of my invention is to provide a new and improved inner door for box cars.

10 A further object of my invention is to provide such a door that shall be adapted to go across the lower part of the door opening without obstructing the upper part thereof.

Still another object is to provide such a 15 door that shall be adapted to open and close with facility.

These objects and others in connection therewith will be made apparent in the following specification and claims, taken in 20 connection with the accompanying drawings, in which—

Figure 1 is an elevation showing my improved door in closed position. Fig. 2 is a 25 vertical section on an enlarged scale, taken on the line 2 in Fig. 1, looking in the direction of the arrow. Fig. 3 is a horizontal section, taken on the line 3 in Fig. 2, looking in the direction of the arrow. Fig. 4 is a horizontal section, taken on the line 4 in Fig. 2, 30 looking in the direction of the arrow. Fig. 5 is a horizontal section, taken on the line 5 in Fig. 1, looking in the direction of the arrow. Fig. 6 is an elevation, partly in section, showing part of the door bracing mechanism hung in the top of the car. Fig. 7 is an elevation of the car wall adjacent to the door opening viewed from the inside. Figs. 8 and 9 are detail sections on the correspondingly numbered lines in Fig. 7.

40 In the particular embodiment of my invention which I have chosen to illustrate in the accompanying drawings, the door opening 15 in the side wall of a box car is bounded by the side door posts 16 and at the bottom by the floor 17. A vertical rod 18 is supported in proximity to the inside face of each side door post 16. At an intermediate point in the height of each rod 18 a bracket 19 engages the same, this bracket being secured to the post 16 by means of the bolt 20 and nut 21, as shown in Fig. 3. The rod 18 is also securely fastened at its top and bottom. The two doors 22 have upper and lower sleeves 23 and 24 on an edge of each 50 which engage the rod 18, thus forming a hinge joint therewith. Thus, it is apparent that each door 22 is adapted to swing horizontally about the rod 18 as an axis, the two doors meeting in a vertical line at the center of the door opening when they are 60 closed. The upper edge of each door has a bent over strengthening lip 25 and the lower edge of each door has a similar strengthening lip 26. Each door has a folding handle 27 attached to the outside thereof. Above 65 the handle a panel 28 is struck up slightly from the general surface of the door and below the handle 27 a larger panel 29 is struck up. These panels add somewhat to the strength of the door. Within the panel 29 70 on the sides thereof are attached the guides 30. Between them at the lower part of the panel 29 an opening 31 is cut out, and a sliding closure 32 mounted in the guides 30 is adapted to close the opening 31. Inward 75 depressions 33 are struck in the lower edge of each closure slide 32 to serve as handles for raising them.

The angle iron 34 extends horizontally across the door opening and has attached to 80 its middle point by the rivets 37 the end 36 of the vertical angle iron 35, the said end being flattened out for the purpose of affording greater security of attachment. At 85 its ends, the horizontal angle iron 34 has one flange cut away, as indicated by the reference numeral 38. This leaves the other flange adapted to project out at each end behind the vertical side posts 16. Short chains 41 have their ends 40 attached to the 90 angle iron 34 near its ends, the remaining ends of the said chains being attached to rings 42 which engage the rods 18. The outwardly projecting flange of the angle iron branch 35 carries a tongue 43 attached 95 by the bolt 44. A clip 45 riveted to one of the doors 22 is adapted to receive the said tongue 43. The sheet metal door sill 47 extends on the floor 17 between the side posts 16. At its center the floor is cut away, as 100 indicated by the reference numeral 48 in Fig. 2. A downwardly projecting stud 49 is riveted to the lower end of the angle iron bar 35 and projects through a hole in the sill 47 directly above the notch 48. The vertical 105 meeting edges of the doors 22 are folded over so as to strengthen them, these folds being opposite on the two doors and lapping past each other, as indicated by the reference numerals 50 and 51 in Fig. 5. At the top 110

of the door opening the two hooks 52 are secured and in these the horizontal member 34 is adapted to rest. The hook 53 is secured by bolts 55 to the carline 54 and this is adapted to receive the extremity of the angle iron bar 35.

A vertical notch 58 is cut on the inside face of the frame members 56 and 57 (see Fig. 7). A short piece of strap iron 59 is laid across the said notch 58, its ends being riveted or bolted to the respective members 56 and 57. On the inside face of each door is a hook 60 which is adapted to engage the strap iron 59 when the door is opened wide.

15 It will be observed that the angle iron members 34 and 35 constitute a frame having a T-shape. When in the position shown in Fig. 1, the ends of the top member of this T-frame rest against the side posts 16 and 20 the bottom end of the T-frame engages the door sill. Thus, the T-frame supports the inner meeting edges of the doors 22 and also the top edges of these doors, holding them securely against the pressure, as of a body of 25 grain, from within the car.

Assuming that the doors are closed and that the car is filled with grain, the procedure to open the doors will be as follows: By means of the hand hold 33 in the slide 30 32 the latter is raised in its guides 30, as indicated at the right of Fig. 1. The slides 32 being raised, the grain will run out through the openings 31 until there will be substantially no grain remaining to exert a 35 pressure against the doors 22. Then from the outside of the car the T-frame 34-35 is lifted up and the member 34 caught on the hooks 52 at the top of the door opening, there being enough slack in the chains 41 40 to permit this. Next, by means of the handle 27, one of the doors 22 is raised vertically, the hinge sleeves 23 and 24 sliding up on the vertical rods 18. After the door 22 has been raised high enough to get it above 45 the grain which at this time will slope down to the door sill 47, then the door 22 is swung in horizontally, and the hook 60 on its inner face is caught over the strap iron 59 on the inner face of the car wall. Similarly, the 50 other door 22 is raised and swung back and supported in its place against the inner face of the car wall. Finally, the depending member 35 of the T-frame 34-35 is swung inwardly and up in a transverse vertical 55 plane and its end is then caught on the hook 53 in the center of the car ceiling. Thus, the whole door opening 15 is entirely unobstructed. The reverse operation of closing the doors will be sufficiently obvious from 60 the description that has just been given of how they may be opened. It is to be observed that the meeting edge of the left-hand door 22, as viewed in Fig. 1, is between the angle iron bar 35 and the corresponding 65 edge of the right-hand door 22 (see Fig. 5).

Thus, the engagement between the members 43 and 45 serves to hold both doors 22 tightly against the T-frame 34-35.

The little metal blocks 61 are embedded in the floor adjacent to the lower edges of 70 the doors where they meet when closed, on the inner sides thereof (see Figs. 1 and 2). These blocks project slightly above the surface of the floor and are gently beveled toward the doors when the latter are open, 75 but are steeply beveled toward the doors when closed. It is apparent that they will therefore act as catches to hold the lower edges of the doors tightly closed.

I claim:

1. In combination, a wall with a door opening therein, doors hinged at the sides so that they may slide vertically on their 80 hinges, and a rigid T-shaped brace to hold the doors, the bottom member thereof engaging the door sill and the ends of the top member engaging the side posts of the door opening.

2. In combination, a wall with a door opening therein, a vertical rod adjacent to each side post of the door opening, a pair of doors each having one edge rotatively and 90 slidably engaging a respective rod, and a rigid T-shaped brace to support the doors when closed, the bottom member thereof 95 engaging the door sill and the ends of the top member engaging the side posts of the door opening.

3. In combination, a wall with a door opening therein, doors hinged at the sides 100 so that they may slide vertically or rotate horizontally, and a removable rigid T-shaped brace to hold the doors, the bottom member thereof being adapted to engage the door sill, the ends of the top member being 105 adapted to engage the side posts of the door opening, and means to support the T-brace in the car ceiling when not in place across the door opening.

4. In combination, a wall with a door 110 opening therein, doors adapted to close said door opening, and a rigid T-shaped brace to hold the doors, said brace lying across the meeting edges of the doors and the bottom member thereof engaging the door sill and 115 the ends of the top member engaging the side posts of the door opening.

5. In combination, a wall with a door opening therein, doors hinged at the sides so that they may slide vertically or rotate 120 horizontally, said doors being adapted when closed to extend across the lower part of the door opening, and a removable rigid brace adapted to lie across the meeting edges of 125 the doors when closed and to engage the door sill and side posts of the door opening.

6. In combination, a wall with a door opening therein, doors hinged at the sides so that they may slide vertically or rotate horizontally, said doors being adapted when 130

closed to extend across the lower part of the door opening, and a single removable rigid brace adapted to extend across the door opening entirely below the top edges of the doors, and engage the side posts and the door sill simultaneously.

7. In combination, a wall with a door opening therein, doors adapted to extend across the door opening, and a rigid T-shaped brace to hold the doors, said brace comprising two rolled shapes having the end of one attached to the middle point of the other, said brace being adapted to lie across the meeting edges of the doors when closed and to engage the door sill and side posts of the door opening.

8. In combination, a wall with a door opening therein, doors adapted to extend across said door opening, and a T-shaped brace adapted to support the doors when closed, the ends of the top member of said brace engaging the side posts of the door and being adapted to slide up and down thereon, hooks at the top of the door opening to support said top member of the brace, and a hook depending from the car ceiling back from the door opening to support the other member of the T-brace.

9. In combination, a wall with a door opening therein, doors hinged at the sides and adapted when closed to extend across the door opening, said doors being made of sheet metal and having their edges bent double to strengthen them, and a rigid brace adapted to lie across the meeting edges of the doors when closed and to engage the door sill and side posts.

10. In combination, a wall with a door opening therein, vertical rods adjacent to the side posts of the door opening, a door engaging each rod adapted to slide vertically or swing horizontally thereon, a T-shaped brace to hold the doors, the bottom member thereof engaging the door sill, the ends of the top member engaging the side posts of the door opening, and a loose connection between each said rod and the adjacent end of the T-brace.

11. In combination, a wall with a door opening therein, doors hinged at the sides and adapted to close the door opening, the edges of said doors overlapping when closed, a rigid T-shaped brace adapted to support the doors when closed, and interlocking members on said brace and on that one of the doors which overlaps the other door with respect to said brace.

12. In combination, a wall with a door opening therein, vertical guides adjacent to the side posts of the door opening, a pair of doors hinged at the sides of the door opening and adapted to swing horizontally and meet at the center thereof, and a T-shaped brace to hold the doors, the bottom member thereof being adapted to engage the door sill, the ends of the top member being adapted to engage the side posts of the door opening and also loosely engaging said guides.

13. In combination, a wall with a door opening therein, a pair of doors hinged at the sides of the door opening and adapted to swing horizontally across the same, a T-shaped brace, the bottom member thereof being adapted to engage the door sill, and the ends of the top member being loosely constrained to slide vertically along the respective side posts of the door.

14. In combination, a wall with a door opening therein, a pair of doors hinged at the sides of the door opening and adapted to swing horizontally across the same, a T-shaped brace, the bottom member thereof being adapted to engage the door sill, the ends of the top member being loosely constrained to slide vertically along the respective side posts of the door, and means above the door opening to engage each of the two members of the T-shaped brace and support the same when the doors are desired to be kept opened.

In testimony whereof, I have subscribed my name.

EDWARD POSSON.
